UNITED STATES PATENT OFFICE.

CARLOS SCHMITTHENNER, OF HEIDENHEIM, GERMANY, ASSIGNOR TO J. M. VOITH, OF HEIDENHEIM, GERMANY, A FIRM.

WOOD-PULP-GRINDING MACHINE.

SPECIFICATION forming part of Letters Patent No. 727,458, dated May 5, 1903.

Application filed February 17, 1903. Serial No. 143,833. (No model.)

To all whom it may concern:

Be it known that I, CARLOS SCHMITTHENNER, a citizen of the Empire of Germany, residing in Heidenheim-on-the-Brenz, in the Kingdom 5 of Württemburg, in the Empire of Germany, have invented certain new and useful Improvements in Wood-Grinding Machines, of which the following is a specification.

This invention relates to a wood-grinding 10 machine in which a plurality of feed-pockets provided with pressure-cylinders are disposed around the periphery of a grinding-stone for feeding the wood to be ground by hydraulic or other fluid pressure.

15 The object of the invention is to provide simple automatic mechanism for controlling the pressure of the feed-cylinders, so as to maintain a uniform action of the rotary grinder during the variations of load, due to 20 the cutting out of one or more of the feed-cylinders.

Figure 1 of the accompanying drawings represents a side elevation of one form of wood-grinding machine embodying this invention. Fig. 2 represents a longitudinal section of one of the feed-cylinders in operative connection with the grindstone.

The same reference characters indicate corresponding parts in both figures.

30 This invention is embodied in a wood-pulp-grinding machine comprising the usual elements of such an apparatus—to wit, a rotary grinder E on a shaft F, which receives motion from driving mechanism, (not shown;) a number 35 of pockets P for containing the wood to be ground disposed around the periphery of said grinder and having their inner ends open thereto; pressure-cylinders A, attached to the outer ends of said pockets; pushers in 40 said pockets connected, respectively, by piston-rods C with pistons B in said pressure-cylinders; a pressure-accumulator L, connected with the source of supply for supplying fluid-pressure to said pressure-cylinders; 45 a pump M for maintaining a standard pressure in said accumulator, and pipes connecting said accumulator with the pressure-cylinders.

In this machine there are two systems of 50 supply-pipes connecting the pressure-accumulator with the pressure-cylinders, one sys-

tem for supplying pressure behind the pistons to effect the feeding and another system for supplying pressure in front of the pistons for retracting the plungers for reloading or 55 repairing. In the working pressure system the pressure is regulated by a governor controlled by the speed of the rotary grinder, and in the retracting pressure system the full pressure of the pressure-accumulator is 60 supplied when required to the pressure-cylinders. The pressure in the accumulator L is maintained at a certain maximum standard by means of a pump M and a safety-valve S. This pressure is in excess of that required 65 to cause the working of all the pockets. Each of the pressure-cylinders A is provided with two valve-chests e and b, the valve-chest e serving to admit water or other fluid under pressure to the outer end of the pressure-cylinder A behind the piston B for the purpose 70 of forcing the wood in contact with the rotary grinder for the working operation and the valve-chest b being adapted to admit fluid-pressure to the inner end of the pressure-cylinder in front of the piston B for the purpose 75 of retracting the plunger when the pocket is to be refilled or for other purpose. A valve V controls the inlet and exhaust through the valve-chest b, and a valve v' controls the inlet and exhaust through the valve-chest e, and an actuating-rod y is connected to both 80 said valves and actuated by an exterior lever V, so as to move the valves in unison. A system of pipes a connects the pressure-accumulator L with the valve-chest b, and a system 85 of pipes d connects said accumulator directly or indirectly with the valve-chest e.

A throttle-valve K is disposed in the pipe-system d, so as to reduce the pressure there- 90 in below the normal pressure of the system a.

A governor I is disposed adjacent to the throttle-valve K, and the actuating-lever thereof is connected with said governor, whereby the throttle-valve may be opened 95 and closed automatically. A belt H connects the governor with a pulley G on the shaft F of the rotary grinder E, whereby any variation in the speed of the grinder may be imparted to said governor, which in turn controls the throttle-valve K, and thereby regulates the pressure of the pistons B.

In the use of a grinding-machine provided with this improvement a pressure is maintained in the accumulator L in excess of that required for working all the pressure-cylinders, and the throttle-valve K is so adjusted as to reduce the pressure in the pipe system d to the normal pressure required for operating all of the pressure-cylinders. Assuming that all of the cylinders are in operation and it is desired to cut out one of the working cylinders for recharging its pocket, the valve-lever V will be actuated to shift the valve v' so as to close the supply of fluid from the pipes d to the active end of the cylinder A and to shift valve v so as to open the supply from the pipes a to the opposite end of the cylinder. The plunger d is thus retracted, and the cutting out of one of the cylinders A tends to reduce the aggregate pressure upon the grinder and cause it to rotate at a higher speed. Any increase of speed in the grinder immediately raises the governor I, which opens the throttle-valve K, so that an increase of pressure is supplied to the pipe system d from the accumulator L. This increase of pressure in the pipes d operates to increase the pressure of the pressure-cylinders

ders remaining in action and restores the aggregate pressure on the grinder, whereby the speed of the latter is reduced to normal. 30

I claim as my invention—

In a wood-grinding machine the combination of a rotary grinder, feed-pockets disposed around said grinder, pressure-cylinders for operating said feed-pockets, each provided with two valve-chests connected respectively with the inner and outer ends of said cylinders, a system of pipes connecting the fluid-pressure source with the inner valve-chests, valves in said valve-chests, a system of pipes connecting said source with the outer valve-chests, means for maintaining an excess of pressure for the inner pipe system, a reducing-valve for the outer system, a governor connecting said reducing-valve and means 40 connecting said governor with the driving mechanism of the rotary grinder.

In testimony whereof I have signed my name to this specification in the presence of two subscribing witnesses.

CARLOS SCHMITTHENNER.
